UNITED STATES PATENT OFFICE.

ARTHUR R. SELDEN, OF ROCHESTER, NEW YORK.

CINEMATOGRAPH.

1,229,329.

Specification of Letters Patent. Patented June 12, 1917.

Application filed July 18, 1916. Serial No. 109,890.

To all whom it may concern:

Be it known that I, ARTHUR R. SELDEN, a citizen of the United States, and resident of Rochester, in the county of Monroe and State of New York, have invented certain new and useful Improvements in Cinematographs, of which the following is a specification.

The present invention relates to cinematographs and more particularly to the supporting means therefor, an object of the invention being to provide for supporting the casing of the cinematograph so that it may swing freely both vertically and horizontally to permit the lens to follow moving objects under the action of but one hand of the operator, leaving the other hand free for the operation of the machine.

To this and other ends, the invention consists of certain parts and combinations of parts all of which will be hereinafter described, the novel features being pointed out in the appended claims.

In the drawings:—

25 Figure 1 shows the machine in perspective held substantially vertical;

Fig. 2 is a similar view showing the machine adjusted to another position;

30 Fig. 3 is a top or plan view of the machine showing also in dotted lines another position of the machine; and

Fig. 4 is a rear elevation of the machine, a portion being shown in section.

Referring more particularly to the drawings, 1 indicates a cinematograph which may be of any suitable construction. To the casing a rigid support 2 is rigidly connected at 3 preferably at the center of the bottom. This support may be formed of a 40 plurality of telescoping sections with clamping screws for connecting adjacent sections so that the support or leg may be extended to the desired length in order to adapt the sight opening 5 in the machine to the height 45 of the user. The lower end of the support acts as a pivot on which the machine may be swung freely, both vertically and horizontally, so that the machine may be caused to follow quickly any moving object. A 50 flange 6 surrounds the support slightly above the lower end of the latter in order that the support will not penetrate too deeply into the supporting surface.

The position of the machine about the 55 pivot formed by the lower end of the rigid extensible support is determined preferably

by a single hand piece or grip 7 which may be arranged on the top of the machine in line with the support. This hand piece requires but a single hand of the user of the 60 machine to swing the cinematograph casing in any direction either vertically or horizontally, thus leaving the other hand of the user free to operate continuously the driving member of the cinematograph. 65

It is preferred to drive the cinematograph in a manner similar to that shown in my pending application, Serial No. 85,297, filed March 20, 1916, as the driving mechanism in the aforesaid application does not impart any jarring or shifting action to the cinematograph casing which would tend to counteract or oppose the free swinging movement of the casing about the lower end of the support as a pivot. The driving 75 mechanism in the aforesaid application embodies an operating member 8 mounted independently of the cinematograph as upon a belt 9 on the user of the machine, and connected by flexible shafting 10 with the 80 drive shaft 11 of the cinematograph. In the present construction the drive shaft 11 is vertically arranged and is connected by miter gears 12 with the horizontal operating shaft 13 that is ordinarily operated by a 85 hand crank on the portion of this shaft (shown in dotted lines) that extend outside of the cinematograph casing.

A cinematograph constructed in accordance with this invention can be operated in 90 any direction to follow a moving object by a single hand of a user, leaving the other hand free to drive the machine without any stops, these results being secured by a support which is of the simplest construction. Combined with this support is an operating mechanism which does not produce any counter-action in the casing of the cinematograph. 95

What I claim as my invention and desire 100 to secure by Letters Patent is:—

1. In combination with a cinematograph, means for supporting the cinematograph so that the latter may swing freely both vertically and horizontally to direct the lens 105 on the object and operating means for said cinematograph comprising a driving member supported independently of the cinematograph and a flexible shaft connecting said driving member with the driving shaft 110 of the cinematograph.

2. In combination with a cinematograph,

means for supporting the cinematograph so that the latter may swing freely both vertically and horizontally to direct the lens on the object, and a handle piece by which the cinematograph is sustained in the desired position.

3. In combination with a cinematograph, means for supporting the cinematograph so that the latter may swing freely both vertically and horizontally about a point located below the bottom of the casing of the cinematograph to direct the lens on the object.

4. In combination with a cinematograph, a rigid support rigidly secured at its upper end to the cinematograph and having its lower end adapted to serve as a pivot about which the cinematograph may swing freely both horizontally and vertically to direct the lens on the object and a guard at the lower end of the support to prevent the penetration of the ground by the support.

5. In combination with a cinematograph, a rigid support rigidly secured at its upper end to the cinematograph and having its lower end adapted to serve as a pivot about which the cinematograph may swing freely both horizontally and vertically to direct

the lens on the object, and a handle on the casing of the cinematograph by which the position of the cinematograph about the pivot may be sustained.

6. In combination with a cinematograph, a rigid extensible support rigidly secured at its upper end to the cinematograph and having its lower end adapted to serve as a pivot about which the cinematograph may swing freely both horizontally and vertically to direct the lens on the object.

7. A cinematograph mounted to swing freely both vertically and horizontally to direct the lens on the object, and having a hand piece by which said cinematograph is sustained in the desired position.

8. A cinematograph mounted to swing freely both vertically and horizontally to direct the lens on the object and having a hand piece by which said cinematograph is sustained in the desired position, and operating means for said cinematograph comprising a driving member supported independently of the cinematograph and a flexible shaft connecting said driving member with the driving shaft of the cinematograph.

ARTHUR R. SELDEN.
